UNITED STATES PATENT OFFICE.

CHARLES REINEKE, OF NEW YORK, N. Y.

REDUCTION AND MULTISTROKE POWER-TRANSMITTING MECHANISM.

Application filed March 7, 1921. Serial No. 450,308.

To all whom it may concern:

Be it known that I, CHARLES REINEKE, a citizen of the United States, residing at New York, in the county of New York and State of New York, have invented certain new and useful Improvements in Reduction and Multistroke Power-Transmitting Mechanism; and I do hereby declare the following to be a full, clear, and exact description 10 of the invention, such as will enable others skilled in the art to which it appertains to make and use the same.

My invention relates to power transmitting mechanisms, and contemplates more especially the production of a novel propulsion device for ships, tractors, motor vehicles and the like.

An object of the present invention is to produce a mechanism wherein the power 20 strokes of relative high speed engines are effectively reduced and transmitted to a slower moving element.

Another object of this invention is to provide a reduction mechanism including 25 a cam element and associated reciprocating slide interconnected with a supplemental crank extending from an engine.

A further object of this invention is to produce a comparatively simple, durable 30 and effective mechanism which can be easily installed and readily repaired.

With these and other objects in view the invention further consists in the structural arrangement and combination of the several parts to be hereinafter described and pointed out in the appended claims.

In the drawings wherein is illustrated an embodiment of my present invention:

Figure 1 is a plan view, partly in section, and illustrating an association of my invention with relatively high speed engines, and a slow speed propeller shaft;

Figure 2 is a vertical sectional view through the reciprocating slide and associated cam element, on an enlarged scale;

Figure 3 is a horizontal sectional view therethrough on the line 3-3 of Figure 2;

Figure 4 is a vertical sectional view on the line 4-4 of Figure 2;

Figure 5 is a detail perspective view of the bearing block for one of the roller shafts; and

Figure 6 is a detail sectional elevation of complementary cam elements and roller shafts associated respectively therewith.

This invention has been primarily de-

signed for use in marine propulsion where-in it is desirable to effect a working and efficient reduction in speed of the propeller shaft as compared with the relative high speed engines used to drive the shaft. It will be understood however, that my invention is not limited to ship propulsion, but may be installed in various other power units, such for example, as the motor vehicle and tractor.

Generally stated, my invention comprises an association of two or more engines preferably of the internal combustion type, having connected to supplemental crank shafts 70 carried thereby, the reduction mechanism of cam and roller elements. It is desirable to arrange at least two cam elements in complementary relation and offset with relation to each other so as to evenly transmit the power from the engines without their stopping on dead center. A greater number of engines and an additional number of cam reduction elements may be used.

Referring to the drawings in which similar reference characters designate corresponding parts in the several views, the engines 1 are preferably arranged upon either side of the driven or propeller shaft 2. In the present embodiment this driven shaft 2 will be referred to as the propeller shaft, a conventional thrust bearing 3 being illustrated at one end and suitable bearing supports 4 being provided at the other end thereof.

Each engine 1 is provided with a supplemental crank shaft 5 journalled in suitable bearings 6. This supplemental crank shaft 5 is connected to the engine shaft 7 by means of a coupling 8. This coupling 8 may be of a detachable type, or arranged to operate as a clutch for engaging and disengaging the supplemental crank and engine shaft. As shown the cranks 9 of the supplemental shaft 5 are arranged at 90 degrees, although it will be understood that I do not limit myself to this exact arrangement.

The cranks 9 are each attached to one end of connecting rods 10, the opposite ends of said connecting rods being secured to a reciprocating carriage or slide 11. A connecting rod 10 is attached to each end of the reciprocating carriage 11, which latter has associated therewith the reduction cam 110 and roller shafts now to be described.

The reduction element or cam 12 is of a

three point construction and is keyed to the propeller shaft 2 by means of keys 13, see Figure 2. While I have shown a three-point cam, it will be understood that other types 5 may be inserted wherein the reduction of the power strokes from the engine shaft may be either further decreased or increased as the occasion may require. Cooperating with the several faces of the cam 12 are 10 rollers or roller shafts 14. These roller shafts 14 are revolvably supported in bearings provided on the carriage 11. The bearing for each roller shaft 14 comprises a bearing block 15 adapted to be inserted in 15 a cut-out portion 16 formed in the carriage 11. Retaining flanges 17 are formed on the bearing block 15 as shown and serve to retain the block in position within the opening 16 as will be understood. These flanges 20 17 bear against the outer faces of the side arms 18 on the carriage 11. Cap bearings 19 are provided at each end of the roller shaft 14, and are secured to the side arms 18 on the carriage by means of bolt and nut 25 connections 20. The roller shafts 14 are further retained within the carriage by means of end plates 21 against which bear respectively the head and nut end of a bolt 22 (see Figure 3). This construction per- 30 mits of the roller shaft freely revolving within its bearing and upon the bolt or central supporting shaft 22.

The opposite ends of the carriage 11 are provided with cross head connections 23 to 35 which are secured the ends of the connecting rods 10, hereinbefore referred to. This cross head connection consists of a shaft pin 24, bearings 25, strap pin 26, and bolt 27. The shaft 24 is countersunk at 40 28 in one of the side arms 18 of the carriage. The opposite end of the shaft 24 is reduced and extends through the opposite side arm 18 of the carriage, and receives a nut 29. In the present arrangement it will be seen 45 that the cross head shafts 24, the roller shafts 14, and the propeller shaft 2 are in alinement and receive the motion imparted through the connecting rods 10 according to the throw of the cranks 9. The recip- 50 rocatory motion of the slide or carriage 11 is thereby imparted to the cam 12 which serves to convert this reciprocating into rotary movement, thereby revolving the propeller shaft 2. It will be seen that three 55 complete reciprocations of the carriage 11 or six distinct movements thereof will be required to produce one complete revolution of the shaft 2. The foregoing construction is designed to permit of an easy 60 transmission of the strokes of the engines, and maintain the roller shafts 14 in continuous contact with the cam 12.

The reciprocating carriage or slide 11 is formed of a lower plate 30 and secured by 65 means of bolts 31 at each end thereof to

the side arms 18. A top plate 32 is similarly secured by bolts 33 to the side arms 18. Roller bearings 34 are carried by the lower plate 30 and are designed to operate upon a bottom guide plate 35 as best shown 70 in Figure 2. The plate 35 is secured by means of bolts 36 to the base 37 of a bracket 38. Side plates 35' are secured to the plate 36 and serve to retain the rollers in position. The bracket 38 may be further 75 secured by means of bolts 39 to the bed of a suitable casting as will be understood.

The side arms 40 of the bracket 38 extend upwardly and are offset at 41 to form guide-ways 42 for the reciprocating carriage 11. A top guide plate 43 is secured to the offset portions 41 of the bracket by means of bolts 44. The under side of this top plate 43 serves to guide the carriage as will be understood. Roller or other bearings 80 may be inserted between the carriage and the plate 43. If desired, the bearing supports 45 for the bearings 4 of the propeller shaft may be formed integral with the bracket 38 as shown, although it will 90 be understood that various other constructions of base and bearing supports may be used.

In operation the respective engines 1 are turned over in the direction of the arrows 95 indicated upon the supplemental crank shafts 5, thereby imparting reciprocatory motion through the connecting rods 10 to the slide or carriage 11. The movement of the roller shafts against the working faces 100 of the cam 12 serves to revolve the same as hereinbefore referred to and the propeller shaft 2 is rotated in the direction of the arrow shown in Figures 1 and 2. The relative high speed of the engine shafts and the 105 reciprocations of the connecting rods are thereby converted into rotary movement which is imparted to the propeller shaft at a reduced speed of rotation. The several parts incident to this reduction mechanism 110 are of heavy construction, and when several cam elements are associated respectively upon a single driven shaft, the motion imparted will be evenly received and distributed as will be understood. These cam elements may receive power direct from the 115 piston as will be understood.

It will be understood that I do not limit myself to the exact disclosures herein as various changes in the arrangement and 120 structural design of the several parts may be resorted to without departing from the spirit of this invention.

I claim:

1. The combination with a plurality of 125 parallel high speed driving shafts and a relatively slow speed driven shaft arranged between the same, of a cam fixed to the driven shaft, a cross head adapted to reciprocate in a plane perpendicular to the axis of the 130

driven shaft and provided with oppositely arranged abutment members constructed and positioned to engage said cam at substantially diametrically opposite points, and 5 means connecting said cross-head to said driving shafts in such manner that one of the driving shafts will pull the cross-head in one direction while the other driving shaft is pushing the cross-head in the same direction.

2. The combination with a plurality of parallel high speed crank shafts and a relatively slow speed shaft arranged between the same, of a cam fixed to the slow speed 15 shaft, a cross-head adapted to reciprocate in a plane perpendicular to the axis of the slow speed shaft and provided with oppositely arranged abutment members constructed and positioned to engage said cam at substantially 20 diametrically opposite points, and rods connecting said cross-head to the crank portions of said crank shafts, the crank portions of said crank shafts being so arranged relatively to one another that the crank portion of one shaft will pull the cross-head in one direction while the crank portion of the other shaft is pushing the cross-head in the same direction.

3. The combination with a plurality of 30 parallel high speed driving shafts and a relatively slow speed driven shaft arranged between the same, of a cam fixed to the driven shaft and including a plurality of radially extending arms arranged at angles 35 to one another, a cross-head adapted to reciprocate in a plane perpendicular to the axis of the driven shaft and provided with oppositely arranged abutment members constructed and positioned to simultaneously 40 engage a plurality of the arms of the cam, and means connecting said cross-head to said driving shafts in such manner that one of the driving shafts will pull the cross-head in one direction while the other driving 45 shaft is pushing the cross-head in the same direction.

4. The combination with a plurality of

parallel high speed driving shafts and a relatively slow speed driven shaft arranged between the same, of a cam fixed to the driven 50 shaft, a cross-head adapted to reciprocate in a plane perpendicular to the axis of the driven shaft and provided with oppositely arranged abutment members constructed and positioned to engage said cam at substantially 55 diametrically opposite points, a supporting block for said cross-head, roller bearings supporting said cross-head on said block, said block being adapted to guide the cross-head in a plane perpendicular to the axis of said driven shaft, and means connecting said cross-head to said driving shafts 60 in such manner that one of the driving shafts will pull the cross-head in one direction while the other driving shaft is pushing the 65 cross-head in the same direction.

5. The combination with a plurality of parallel high speed driving crank shafts and a relatively slow speed driven shaft arranged between the same, of a plurality of 70 cams fixed to the driven shaft and each including a plurality of radially extending arms arranged at angles to one another, the arms of one of said cams being arranged out of alignment with the arms of the other cam, 75 cross-heads adapted to reciprocate in planes perpendicular to the axis of the driven shaft and each provided with oppositely arranged abutment members constructed and positioned to engage one of said cams at substantially 80 diametrically opposite points, and means connecting said cross-heads to the crank portions of said driving shafts, the crank portions of each of said driving shafts being arranged at such relative angles that 85 one cross-head will be moved in one direction while the other cross-head is being moved in the opposite direction.

In testimony whereof I affix my signature, in presence of two subscribing witnesses.

CHARLES REINEKE.
